UNITED STATES PATENT OFFICE.

CHARLES F. BRONNER, OF SYRACUSE, NEW YORK.

CLOTHES-WRINGER.

1,336,883.

Specification of Letters Patent. Patented Apr. 13, 1920.

Application filed September 11, 1919. Serial No. 323,083.

To all whom it may concern:

Be it known that I, CHARLES F. BRONNER, a citizen of the United States, residing at Syracuse, in the county of Onondaga and 5 State of New York, have invented a new and useful Clothes-Wringer, of which the following is a specification.

This invention has reference to clothes wringers, and more particularly to a clothes 10 wringer having means for guarding the wringer rollers thereof against articles passing through the rolls, becoming entangled around the rolls, thereby clogging the wringer, and impairing the efficiency of the 15 same.

A further object of the invention is to provide a device of this character which may be readily attached to the usual wringers, now in use, without the necessity 20 of changing the construction of the wringers.

With the above and other objects in view, which will appear as the description proceeds, the invention resides in the combination 25 and arrangement of parts and in the details of construction hereinafter described and claimed, it being understood that various changes in the precise embodiment of the invention shown can be made without departing from the spirit of the invention.

Referring to the drawing:—

Figure 1 illustrates a side elevational view of a wringer constructed in accordance with the present invention.

35 Fig. 2 illustrates a sectional view taken on line 2—2 of Fig. 1.

Fig. 3 illustrates a top plan view of one of the guarding elements, and

40 Fig. 4 illustrates an end view of the upper guarding element.

Referring to the drawing in detail, the reference characters 5 and 6 designate the vertical side bars of the frame of the wringer, which side bars 5 and 6 are connected by the horizontally disposed bars 7 and 8, disposed on opposite sides of the vertical side bars 5 and 6, and secured thereto, by means of the screw elements 9, passing through the bars 7 and 8 and engaging the 50 bars 5 and 6.

A horizontally disposed member 10, connects the side bars 5 and 6 adjacent the upper ends thereof, for bracing the bars 5 and 6, and holding the same in proper relation with each other, against lateral displacement,

Supported between the side bars 5 and 6, and having connection therewith to further brace the side bars 5 and 6 is the bar 11, lying in a horizontal plane, in spaced relation with the wringing rollers 12 and 13, operating one above the other, and in proper spaced relation to permit articles to pass therebetween.

The bar 11 is disposed in spaced relation 65 with the upper roller 12, which space accommodates the upper guarding member 14, which includes a central portion 15, and the depending flange members 16 and 17, formed integral with the longitudinal edges thereof, 70 the lower edges of these flanges 16 and 17, lie in close proximity with the upper roller 12, for acting as a scraper, which scraper engages articles that might adhere to the wringer rollers, and throws the articles laterally therefrom, thereby preventing articles 75 from entangling themselves around the roller, during the wringing operation.

The lower roller is guarded by the right angled flange members 18 and 19, secured to 80 the inner side walls of the members 7 and 8, as shown by Fig. 2 of the drawing, the right angled portions 20 and 21 being supported in a horizontal plane, the free edges thereof, being supported in close proximity 85 with the lower roller 13, of the wringer, to engage articles, under operation, which might adhere to the rollers, and remove the same, thereby eliminating the possibility of the articles choking the roller and rendering 90 the same inoperative.

Each of the right angled portions 20 and 21, is curved transversely of its length, as at 22, the curved portion also having a plurality of openings 23 disposed throughout 95 the length thereof, in spaced relation with each other.

From the foregoing, it is obvious that the right angled portions 20 and 21, form efficient guards, for preventing the articles associated therewith, from entangling themselves around the rollers, and at the same time receive, and discharge the fluid pressed from the articles during the wringing operation, between the side members 5 and 6, so 100 that the operator is not subjected to the discomfort of having the fluid splashing over his clothes.

Having thus described the invention, what is claimed is:—

1. In a wringer, a frame including side members, a horizontally disposed brace bar

supported between side members, a pair of horizontally disposed wringing rollers supported by the side members, and arranged one above the other, lateral guards operating in close proximity with opposite sides of one of the rollers, and a guard including spaced depending flanges secured to the brace bar, the lower edges of the depending flanges lying in a plane in close proximity with the upper roller, and said lateral guards having draining opening.

2. In a wringer, a supporting frame, horizontally disposed wringing rollers sup-

ported one above the other, lateral guards including flanges curved transversely of 15 their lengths, and having a plurality of spaced openings, and a guard for the upper roller.

In testimony that I claim the foregoing as my own, I have hereto affixed my signature in the presence of two witnesses.

CHARLES F. BRONNER.
